[57] CLAIM

The ornamental design for the handbag, as shown and described.

DESCRIPTION

FIG. 1 is a right side perspective view of my new design;
FIG. 2 is a right side view of the embodiment of FIG. 1, the left side being a mirror image thereof;
FIG. 3 is a right end view of my new design, with the opposite end view being a mirror image thereof;
FIG. 4 is a top view; and,
FIG. 5 is the bottom view.
The dashed lines shown in the Figures indicate stitching.
